GOLF TEE SHELTER

Claude W. Ahrens, Grinnell, Iowa
Filed Apr. 8, 1960, Ser. No. 60,093

Term of patent 14 years
(Cl. D13—1)

FIG. 1

FIG. 2

Fig. 1 is a front perspective view of a golf tee shelter showing my new design, the tubular base member being broken away to indicate indeterminate length;

Fig. 2 is a rear perspective view thereof, the tubular base member being broken away to indicate indeterminate length; and

Fig. 3 is a vertical sectional view taken along the line 3—3 in Fig. 2, the tubular base member being broken away to indicate indeterminate length.

I claim:

The ornamental design for a golf tee shelter, substantially as shown and described.
